UNITED STATES PATENT OFFICE.

JOHN H. PITTS, OF DALLAS, TEXAS.

FOUNTAIN BRUSH.

Application filed December 21, 1927. Serial No. 241,623.

This invention is a fountain brush intended more particularly for use in cleaning and polishing automobile bodies and parts although it may, of course, be advantageously employed in other fields. The object of the invention is to provide a compact arrangement whereby a supply of liquid polish may be maintained in proximity to the brush and the flow of the same to the brush controlled easily by the operator, and also to provide means whereby the liquid polish will be positively fed to the brush as the latter rotates and so distributed over the tufts of the brush as to be effectually applied to the surface to be polished without being thrown out over adjacent objects by centrifugal action. Other objects will appear incidentally in the course of the following description, and the invention resides in certain novel features which will be particularly defined in the appended claims.

In the accompanying drawing:

Figure 1 is a side elevation of a brush and tank embodying the invention;

Fig. 2 is a sectional elevation of the same;

Fig. 3 is a transverse section on the line 3—3 of Fig. 2, and

Fig. 4 is a detail showing an alternative form of valve.

In carrying out the invention, there is provided a tank 1 which may be of any approved construction and is preferably cast of aluminum so as to avoid unnecessary weight. This tank is provided with a filling opening in its top which is normally closed by a plug 2, as will be understood. Adjacent one end of the tank, there is erected therein a barrel or cylinder 3 in which is mounted a plunger 4 having a stem 5 rising therefrom through the top of the tank and operatively connected with a finger lever 6 fulcrumed between its ends on the top of the tank. A spring 7 is disposed within the barrel or cylinder 3 between the top thereof and the upper end of the plunger valve 4 so that the plunger is normally held at the bottom of the barrel to cut off flow of liquid therethrough, the barrel being provided with a port 8 at its lower end whereby the liquid, indicated at 9, within the tank may pass out to be fed to the brush. A slight pressure upon the free end of the finger lever 6 will rock the lever and lift the plunger valve 4 so that the port 8 will be uncovered and a portion of the liquid

may escape. The tank is constructed in two similar members bolted together with packing in the joint and, in its lower portion, defines a cylindrical body 9 through which a shaft 10 extends, the forward portion of said shaft being hollow, as shown at 11, and having a spiral conveyer wire 12 disposed therein and extending axially to the end of the shaft, the shaft being provided with a radial port 13 to establish communication between the hollow portion 11 and an annular groove or chamber 14 on the inner wall of the cylindrical bearing portion 9 of the tank. Bearings 15, preferably of the friction roller type, are secured within the bearing portion 9 of the tank around the shaft so that it may rotate freely, and stop collars 16 are also secured upon the shaft to bear against annular shoulders formed in the cylinder 9, or against the ends of the cylinder, and thereby prevent endwise movement of the shaft, the result being that the port 13 will be maintained in alinement with the barrel 3 and the annular chamber 14.

The tank is provided at one end with a nozzle 17 over which is fitted a sleeve 18 attached to one end of a flexible tubular housing 19 and within the coupling sleeve 18 the end of the shaft 10 is connected by a flexible coupling 20 with a flexible driving shaft 21 extending to a suitable motor. In practice, I have employed an electric motor to furnish the power for driving the brush shaft 10, and the flexible shaft 21 may be coupled directly to the end of the motor or to the output shaft of a train of speed-reducing gears.

The brush, indicated at 22, may be secured directly on the hollow end of the brush shaft 10, but, as a matter of convenience, I form the hollow portion of the shaft in two sections which are joined by a coupling sleeve 23 in an obvious manner. The brush consists of a plurality of circular sections 24 which may be of any suitable material, such as cotton waste, soft textile fabric, felt or any other material which may be preferred. The several circular sections are secured upon the shaft by and between collars 25, one of which forms an inner abutment for the brush while the others are provided with radial perforations 26 registering with corresponding perforations in the wall of the hollow shaft whereby the liquid may escape from the shaft between

adjacent sections and be applied to the sides of the several sections so that it will slowly percolate through and permeate the several sections and, consequently, will have but 5 slight tendency to escape forcibly through centrifugal action. This result is also furthered by rotating the brush at a comparatively low speed. The outer extremity of the hollow shaft is closed, as shown at 27, 10 and is externally threaded to receive a nut 28 whereby the outermost section of the brush will be clamped against the outermost collar and the several sections effectually held in close compact form and will 15 present practically an uninterrupted outer surface. The outermost section 29 of the brush is preferably of greater diameter than the inner sections so that the brush may be operated around angles and small 20 brackets which cannot be easily and satisfactorily treated by a brush having a uniform diameter from end to end. The several brush sections are made of a standard uniform thickness so that, when renewals 25 are necessary, new sections may be secured in place and the outlets from the shaft will not be closed when the clamping collars are again turned home.

The use of the brush will, it is thought, 30 be readily understood from the foregoing description, taken in connection with the accompanying drawing. The tank is held by the operator so that the brush will be positioned in contact with the surface which 35 is to be cleaned and polished and by occasionally opening the plunger valve 4 a sufficient quantity of liquid will be permitted to flow to the brush to attain the desired application to the part upon which the 40 brush is operating. The liquid will flow by gravity through the port 8 into the annular chamber 14 and thence into the bore of the hollow shaft and, within said bore, will be positively fed to the brush by the 45 screw conveyer 12. The device is compact, easily operated and has been found to be highly satisfactory in actual use.

The spiral conveyer may be conveniently formed by coiling a wire of proper gage and in such form has been found to be 50 very efficient in causing a positive flow of the liquid.

In Fig. 4, I have shown a form of valve which eliminates the finger lever. In this form, the valve 30 is in the form of a spool 55 having its heads normally respectively above and below the port in the barrel. The valve stem projects through the top of the tank and is equipped with a cap or presser piece 31, between which and the tank an expansion spring 32 is coiled around the stem. The spring holds the valve raised and pressure is exerted on the cap 31 to lower the valve to open position. Any convenient form of stop, as 33, may 60 be provided to limit the movement of the valve under the influence of the spring.

Having thus described the invention, I claim:

1. Apparatus for the purpose set forth 70 comprising a tank, a hollow shaft mounted on the tank and in communication therewith, the shaft being perforated adjacent its outer end, and a brush secured on the outer end of the shaft and consisting of 75 a plurality of sections, and securing devices between the several sections, said securing devices being perforated to register with the perforations in the shaft and permit flow of liquid from the shaft to the brush. 80

2. Apparatus for the purpose set forth comprising a tank, a barrel within the tank having a port at its lower end, a hollow shaft mounted on the tank and in communication with the lower end of the barrel, a brush carried by said shaft, a plunger valve within the barrel, an expansion spring acting on the plunger to hold the same normally in closed position, and means whereby the valve may be opened 85 at will.

In testimony whereof I affix my signature.

JOHN H. PITTS. [L. S.]
